COSMETIC HOLDER

August Mitchell, New York, N. Y., assignor to
Chase Brass & Copper Co. Incorporated, Wa-
terbury, Conn., a corporation

Application June 20, 1938, Serial No. 214,699

6 Claims. (Cl. 132—82)

The present invention relates to an improved construction for cosmetic holders such, for example, as those manufactured and supplied to the trade for carrying about in handbags, pocket-books, and like receptacles, small amounts of cosmetics which are commonly utilized to beautify the complexion, skin, or hair of the user.

One of the objects of this invention is to provide an improved cosmetic-holder construction whereby greater strength, rigidity, and durability may be imparted to portions of the cosmetic holder which are commonly distorted and deformed by the strains produced therein by manipulations of the cover and cosmetic backing-plate.

Another object of the invention is to provide an improved cosmetic-holder construction comprising a minimum number of parts of simple and effective form to impart a desirable degree of lightness, strength, and compactness in such a way as to enhance and tend to maintain the ornamental appearance of the cosmetic holder.

A still further object of the invention is to provide a combined cosmetic-retainer-hinge-knuckle member of peculiar construction for releasably retaining the cosmetic in position within the cosmetic holder while, at the same time, relieving the lateral wall of the cosmetic holder of strains commonly imposed thereon by manipulations of the cover and cosmetic backing-plate.

With the above and other objects in view, as will appear to those skilled in the art, from the present disclosure, this invention includes all features in the said disclosure which are novel over the prior art.

For the purposes of illustration, the accompanying drawing shows an adaptation of the invention to a cosmetic holder of a type in which a cake of compressed powder is suitably formed upon a backing-plate for placement in the said cosmetic holder wherein it is to be releasably retained until it is replaced by a refill.

In the drawing:

Fig. 1 is a top plan view of the cosmetic holder with the cover-member in closed position on the body-member thereof;

Fig. 2 is a rear elevation of the same;

Fig. 3 is a vertical medial section corresponding to the line 3—3 of Fig. 1;

Fig. 4 is an enlarged top plan view of the cosmetic holder with the cover-member in open position;

Fig. 5 is an enlarged vertical section corresponding to the line 5—5 of Fig. 3;

Fig. 6 is a perspective view of the cosmetic-retainer-hinge-knuckle member; and

Fig. 7 is a similar view of the body-member.

According to the embodiment of the invention shown on the drawing, a body-member, designated generally by the reference character

10, is provided with a cover-member 11 to form a closed cosmetic holder. The said cover-member 11 is provided with a knuckle-member 11a by means of which it is pivotally mounted on a hinge-pin 12 arranged adjacent to the upper 5 marginal edge of the lateral wall 13 of the said body-member 10 and substantially in tangential relation thereto. For this purpose, a combined retainer-and-hinge member, designated generally by the reference character 14, is employed. In 10 the form shown, the said retainer-and-hinge member 14 comprises an intermediate cosmetic-retaining portion 15 and a pair of upwardly-diverging arms 16—16 which, as shown, are deflected outwardly at their tops through aligned 15 circumferentially-spaced slots 17—17 in the lateral wall 13 of the body-member 10, the said arms being in contacting engagement with the inner surface of the lateral wall 13 at said slots.

As shown in the drawing, the terminal-portions 20 of the upwardly-diverging arms 16 of the member 14 are curled about the hinge-pin 12 to form hinge-pin knuckles 18—18 which extend outwardly from the wall 13. In the preferred form of the invention shown in the drawing, those interior portions of the combined retainer-and-hinge member which extend downwardly from the slots 17—17 to a point adjacent the bottom-wall of the body-member 10 of the cosmetic holder are inclined inwardly from the inner surface of the wall 13 towards an intermediate protuberant portion 15a of the cosmetic-retaining portion 15 of the member 14. This protuberant portion 15a is arranged in the path of the marginal edge of a cosmetic-backing plate 19 during 30 the tilting movement of the said or a similar backing-plate about an opposite marginal portion thereof which occurs whenever the cosmetic is to be replaced by a refill. It will be understood from the foregoing that during this tilting movement of the cosmetic-backing plate 19, the resilient character of the material (spring-brass or the like) of which the retainer-and-hinge member 14 is constructed, renders it yieldable 35 toward the inner surface of the lateral wall 13 to a sufficient degree to permit the marginal edge of the plate 19 to snap past the protuberant portion 15a.

It will be understood from the foregoing that the hinge-pin knuckles 18—18 are integrally 50 united each to the other by the arms 16—16 which branch upwardly from the cosmetic-retaining portion 15 of the combined retainer-and-hinge member 14. Inasmuch as the said hinge-pin knuckles 18—18 are symmetrically disposed with respect 55 to the central vertical plane of the said combined retainer-and-hinge member, the said member serves as a reinforcement to the lateral wall 13 in and around the hinge. At the same time, the lower end of the cosmetic-retaining portion of the 60

said member is positioned to flex during a slight resilient retirement of the protuberant portion 15^a resulting from the insertion or removal of the cosmetic-backing plate 19. Furthermore, the 5 marginal edge of the cover-member 11 in the fully-open position thereof comes into engagement with the outer surface of the lateral wall 13 at a point slightly below and substantially 10 midway between the hinge-pin knuckles 18-18 which latter are integrally united and thus serve to firmly support the lateral wall 13 of the body-member 10 at the deflected upper end of the arms 16-16.

The invention may be carried out in other 15 specific ways than that herein set forth, without departing from the spirit and essential characteristics of the invention, and the present embodiment is, therefore, to be considered in all respects as illustrative and not restrictive and all 20 changes coming within the meaning and equivalency range of the appended claims are intended to be embraced therein.

I claim:

1. A cosmetic-holder construction, comprising:

25 a cosmetic-receiving body-member; a cover-member for the said body-member; and a combined cosmetic-retainer-hinge-knuckle member having a portion thereof extending through and retained against inward displacement from the 30 said lateral wall of the said cosmetic-receiving body-member by means of a hinge-receiving knuckle formed therein at the outer surface of the lateral wall and a cosmetic-retaining portion depending within the said body-member; a 35 cover-hinge-pin mounted in said knuckle; and a cosmetic-backing plate generally conforming to the contour of the said lateral wall and constructed to have marginal engagement with and to snap past the cosmetic-retaining portion of the cosmetic-retainer-hinge-knuckle member during 40 the forcible insertion of the cosmetic into and removal from the said cosmetic-receiving body-member.

2. A cosmetic-holder construction, comprising: 45 body- and cover-members; an integrally-constructed cosmetic-retainer-hinge-knuckle member extending through and anchored in the upper marginal portion of the lateral wall of the said body-member, said cosmetic-retainer-hinge-knuckle member including at the top a hinge-pin-knuckle projecting outwardly from the said lateral wall of the body-member, and a cosmetic-retaining portion spaced from and displaceable towards the inner surface of the said lateral wall 50 by the slidable engagement therewith of a cosmetic during the forcible insertion of the said cosmetic into the said body-member.

3. In a cosmetic-holder, the combination with a 60 body-member having a lateral wall provided adjacent its upper marginal edge with circumferentially-spaced substantially-aligned slots; of a cosmetic-retainer-hinge-knuckle member constructed of resilient sheet material and having circumferentially-spaced branches in contacting engagement with the inner surface of said lateral wall at the said slots respectively and inclined downwardly away from said inner surface, the terminal-portions of said branches being extended through said slots and shaped exteriorly thereto to provide circumferentially-aligned 65 hinge-knuckles in contacting engagement with the outer surface of said lateral wall at said slots; and a cosmetic-retainer portion depending from and integrally uniting the said branches, said cos-

metic-retainer portion being terminated short of the bottom inner surface of the said body-member and having a protuberance formed therein to releasably retain a cosmetic-cake in position on the bottom surface of said body-member. 5

4. A cosmetic holder-construction, comprising: a cosmetic-receiving body-member provided with a lateral wall; a combined retainer-and-hinge member extending through and having its entire weight carried by said lateral wall; a cover-member; a hinged-connection between the cover-member and the combined retainer-and-hinge member, including knuckle-members integrally formed with the combined retainer-and-hinge and cover-members, respectively; the said hinged-connection being constructed and arranged at the outer surface of the said lateral wall to reinforce and to be reinforced by the said lateral wall; and an integrally formed cosmetic-retainer-portion of the said retainer-and-hinge member depending within the said body-member and displaceable towards the inner wall thereof by slidable-engagement with the cosmetic as the latter is moved into and out of position within the body-member. 25

5. A cosmetic holder-construction, comprising: a cosmetic-receiving body-member having a lateral wall provided adjacent its upper marginal edge with substantially-aligned circumferentially-spaced slots; a combined retainer-and-hinge member constructed of resilient sheet metal and comprising circumferentially-spaced arms in contacting engagement with the inner surface of said lateral wall at the said slots respectively, the said arms being downwardly convergent within the body-member and integrally united adjacent the bottom thereof to form a depending cosmetic-retainer portion, the terminal portions of said arms being extended through the said slots and forming hinge-knuckles protruding beyond the outer surface of the said lateral wall; and a cover for the said body-member provided with an integrally-formed hinge-knuckle interposed between the knuckle-members formed by the terminal portions of the said arms; and a hinge-pin extending through all of said hinge-knuckles and pivotally supporting the cover hinge-knuckle in oscillatory bearing engagement with the outer surface of the said lateral wall. 40

6. A cosmetic holder-construction, comprising: 45 a body-member having a lateral wall provided with aligned circumferentially-spaced slots adjacent the upper marginal edge thereof; a cover for the said body-member; a combined retainer-and-hinge member constructed of resilient sheet material and comprising a cosmetic-retainer portion depending below and circumferentially intermediate to the slots in the lateral wall of said body-member; upwardly branching arms having their terminal portions extending outwardly 55 through the circumferentially-aligned slots in the lateral wall of the said body-member, the said terminal portions being constructed to form circumferentially-aligned hinge-knuckles protruding from the outer surface of the said lateral wall; and a hinge-pin mounted in the said hinge-knuckles for pivotally mounting the said cover on the said body-member; the said cosmetic-retainer portion being constructed and arranged to be displaceable outwardly toward the lateral wall of 60 the body-member by the engagement therewith of the marginal edge of a cosmetic-backing plate. 65
